DESIGN FOR AN ELECTRIC LIGHTING FIXTURE

Dean H. Holden, Cleveland, Ohio

Application July 20, 1939, Serial No. 86,128

Term of patent 7 years

To all whom it may concern:

Be it known that I, Dean H. Holden, a citizen of the United States and residing in Cleveland, in the county of Cuyahoga and State of Ohio, have invented a new, original, and ornamental Design for an Electric Lighting Fixture, of which the following is a specification, reference being had to the accompanying drawing, forming a part thereof, in which:

Fig. 1 is a side elevational view of an electrical lighting fixture showing my new design;

Fig. 2 is a front elevational view with portions broken away for convenience of illustration;

Fig. 3 is a perspective view of the clamp member and a fragmentary portion of the standard of the fixture shown in Fig. 1; and

Fig. 4 is a perspective view of the fixture shown in Fig. 1 with the standard fragmentarily shown for convenience of illustration.

I claim:

The ornamental design for an electric lighting fixture, substantially as shown and described.

DEAN H. HOLDEN.
